CLEANER FOR PHONOGRAPH RECORDS

Tadao Shimono, 971 Oaza Utsuishi, Shimonoseki-shi,
Japan

Filed Apr. 3, 1968, Ser. No. 11,290

Term of patent 14 years

U.S. Cl. D26—14
Int. Cl. D4—01

FIG. 1

FIG. 2

FIG. 3

FIG. 4

FIG. 1 is a front view of a cleaner for phonograph records showing my design;

FIG. 2 is a right side elevational view thereof;

FIG. 3 is a top plan view thereof; and

FIG. 4 is a rear view thereof.

The undisclosed left and bottom side of the cleaner are mirror images of the right and top side respectively.

I claim:

The ornamental design for a cleaner for phonograph records, substantially as shown and described.
